UNITED STATES PATENT OFFICE

PAUL KENT KINGDON, OF BAYSWATER, AUCKLAND, NEW ZEALAND

WIRELESS RECEIVING APPARATUS

Application filed April 21, 1927, Serial No. 185,453, and in New Zealand January 20, 1927.

This invention relates to wireless receiving apparatus and has for its object the provision of improved means for "trapping" the waves and cutting out or minimizing the effect of oscillations from nearby high power broadcasting stations or the like without appreciable reduction of signal strength from stations it is desired to receive.

At present persons having wireless sets in cities or other places where there are high power broadcasting stations in the vicinity are unable to receive distant stations satisfactorily owing to the influence of the local broadcasting station and therefore in many cases the sets are practically limited to receive only such local station while it is on the air.

What are known in the art as "wave traps" have been devised to eliminate this difficulty but with the types of such traps at present in use the elimination of the oscillations from the local broadcasting stations unfortunately considerably reduces the signal strength of the stations it is desired to receive. The present invention has been devised to permit the oscillations of the local station being adequately eliminated or minimized while at the same time permitting the signals from the other stations with which it is desired to get in touch coming through strongly and with no appreciable diminution.

According to my invention I provide intercepting means which may be either readily attachable to existing wireless sets or in incorporated in fresh sets as may be desired and which comprises a primary and a secondary coil, one coil in conjunction with suitable stud switches or the like and a variable condenser to vary the inductance of the coil being adapted to trap the waves of the broadcasting or other station it is desired to eliminate while the other coil permits the signals from the desired station to be maintained in substantially their original volume and to be tuned in on the set in the ordinary way.

The accompanying drawing illustrates the arrangement of the invention as connected to a usual type of wireless receiving set wherein a primary coil 1 is provided having tappings preferably in two groups 2 and 3 leading to

suitable stud switches 4 and 5, the former being connected by wire 6 direct to the terminal 7 and the latter in series with a variable condenser 8 also to the terminal 7 by wire 9.

The aerial 10 is connected to the terminal 11 of the primary coil 1 the latter having superimposed thereover a secondary coil 12 which is connected in series with a fixed condenser 13 by wire 14 to the terminal 7.

In practice it has been found convenient for the primary coil to have 128 turns of 26 S. W. G. double silk covered wire with tappings taken from the 80th turn onwards. The secondary coil has 80 turns of 28 S. W. G. double silk covered copper wire and is of smaller diameter wire to increase the inductive influence of the primary and to prevent any undue decrease in the volume of the received signals.

The secondary coil is tightly wound over the input end of the primary but insulated from same by a suitable thin insulating medium.

The terminal 7 is connected by wire 15 to the usual aerial terminal 16 of the wireless receiving set 17 which is provided with the usual earth connection 18 and adjustment dials 19.

In operation the dials 19 of the set 17 are placed by the operator to the position which he has learned by experience to be the setting for receiving the distant station, but of course the oscillations of the nearby high power broadcasting station prevent the distant station from being heard although the setting is correct for receiving same, the variable condenser 8 and stud switches 4 and 5 are therefore then adjusted so as to vary the inductance of the primary coil 1 to suit and trap the wave length of the nearby high power station, the secondary coil 12 permitting the signals of the station or stations of wave length other than that of the station trapped and eliminated to be received and maintained at substantially their original volume.

I claim:

The combination with a radio receiver having an input terminal, and an aerial wire, of a primary coil interposed between said aerial

wire and terminal, said primary being electrically connected with the aerial wire and including two groups of tappings, a pair of stud switches one for each of said groups adapted selectively to engage the tappings thereof, one of said stud switches being in electrical connection with said input terminal, a variable condenser connected in series with the other of said stud switches and with said terminal, a secondary coil in inductive relation with said primary coil and electrically connected with the input terminal of the receiver, and a fixed condenser in series with said secondary coil and input terminal.

15 In testimony whereof I affix my signature.

PAUL KENT KINGDON.
